(57) **CLAIM**

The ornamental design for a calculating equipment, as
shown and described.

DESCRIPTION

FIG. 1 is a perspective view of the calculating equipment
showing our new design;

FIG. 2 is a front view of the calculating equipment of FIG.
1;

FIG. 3 is a rear view of the calculating equipment of FIG. 1;
FIG. 4 is a left view of the calculating equipment of FIG. 1;
FIG. 5 is a right view of the calculating equipment of FIG.
1;

FIG. 6 is a top view of the calculating equipment of FIG. 1;
FIG. 7 is a bottom view of the calculating equipment of FIG.
1;

FIG. 8 is a perspective view of the calculating equipment
showing an alternate embodiment;

FIG. 9 is a front view of the calculating equipment of FIG.
8;

FIG. 10 is a rear view of the calculating equipment of FIG.
8;

FIG. 11 is a left view of the calculating equipment of FIG.
8;

FIG. 12 is a right view of the calculating equipment of FIG.
8;

FIG. 13 is a top view of the calculating equipment of FIG.
8;

FIG. 14 is a bottom view of the calculating equipment of
FIG. 8;

FIG. 15 is a perspective view of the calculating equipment
showing an alternate embodiment;

FIG. 16 is a front view of the calculating equipment of FIG.
15;

FIG. 17 is a rear view of the calculating equipment of FIG.
15;

FIG. 18 is a left view of the calculating equipment of FIG.
15;

(Continued)

FIG. 19 is a right view of the calculating equipment of FIG. 15;

FIG. 20 is a top view of the calculating equipment of FIG. 15; and,

FIG. 21 is a bottom view of the calculating equipment of FIG. 15.

The broken lines depict portions of the calculating equipment that form no part of the claimed design.
